Theodore W. Lillague, of Philadelphia, Pa.
Assignor to Savory Co. of same place
Letters Patent No 1221 dated April 3 1860.

The schedule referred to in these Letters Patent and making part of the same.

To all whom it may concern:

Be it known that I, Theodore W. Lillague, of the City of Philadelphia, in the State of Pennsylvania, have invented or produced a new and original design for Fire-Dogs, and I do hereby declare that the following is a full and exact description of the same; reference being had to the annexed drawings, making a part of this Specification, and to the letters of reference marked thereon.

The said design I call the 'Rose Pattern'. It consists of a combination of ornamentations representing carvings in the forms of roses, ornamented scrolls, and shields, arranged together, as hereinafter described, to be cast in metal to serve as the front part of a fire-dog.

In the drawing A.A. represent the leg scrolls; A' A² the body scrolls; A³ the top scroll, B.B. the roses, C. the main shield, and D. the top shield.

The faces of the leg scrolls, A.A., are ornamented with the shell-work f.f. the outer sides of the scrolls A' A², are ornamented with the shell-work g.g., and the outer edge of the top scroll, A³, with the shell pattern boundary h.h.

2

Dec 1921

The lower end of the shield, C, is divided into the scroll branches i.e. by the pendant leaf R, and forms a central ornament joining the scrolls A, A, below, the roses B, B, (one on each side), and the scrolls A', A', above. The scroll A' is a branch extending upward from scroll A, and supports the top shield D, which is trilobed.

The whole are arranged in connection together so as to produce the external and internal contour shown in the drawing, and so as to be cast in one piece.

What I claim as my invention or production, and desire to secure by Letters Patent is -

The Rose Pattern Design, for fire-dogs, described and set forth.
